LAPIDARY APPARATUS FOR PROCESSING STONES

John W. Flaherty, Galesburg, Ill., and Robert C. Ingersoll
and William F. Goodrich, Adrian, Mich., assignors to
Dick Blick Company

Filed Mar. 17, 1975, Ser. No. 559,264

Term of patent 14 years

Int. Cl. D15—09

U.S. Cl. D37—1 A

FIG. 1

FIG. 2

FIG. 3

FIG. 4

FIG. 1 is an isometric view of a lapidary apparatus for processing stones embodying our new design;

FIG. 2 is an isometric view of the lapidary apparatus in a different position;

FIG. 3 is a top plan view of the lapidary apparatus, and

FIG. 4 is an end view of the lapidary apparatus.

We claim:

The ornamental design for a lapidary apparatus for processing stones, as shown.
